Emil Christensen

Inventor,

By *Emil Christensen* Atty.

UNITED STATES PATENT OFFICE.

EMIL CHRISTENSEN, OF PORTLAND, OREGON.

VARIABLE-STROKE MECHANISM.

1,275,224.

Specification of Letters Patent. Patented Aug. 13, 1918.

Application filed December 29, 1916. Serial No. 139,681.

To all whom it may concern:

Be it known that I, EMIL CHRISTENSEN, a citizen of the United States, residing in the city of Portland, county of Multnomah, 5 and State of Oregon, have invented certain new and useful Improvements in Variable-Stroke Mechanism, of which the following is a specification.

My invention relates to variable stroke 10 mechanisms, and it has among its salient objects to provide a simple, practical and efficient mechanism which is capable of adjustment, whereby to vary the stroke, or reciprocating movement of a driven element.

15 While my invention is capable of general application, in order to illustrate the same, I have shown it in the accompanying sheet of drawing connected with a piston, or plunger.

20 In the drawing I have shown the invention in side elevation, the parts being shown in full lines in the positions occupied for transmitting the maximum stroke to the piston, or plunger, and in dotted lines in 25 their positions for transmitting the minimum stroke to the piston, or plunger.

Referring now in detail to the drawing, 1 designates a cylinder, 2 a piston, or plunger, therein, 3 a piston rod, and 4 a 30 cross beam, or lever. Connected to the opposite ends of said cross beam, or lever, 4, are two eccentric members 5 and 6, the eccentric disks 7 and 8 of which are secured to shafts 9 and 10. Mounted concentrically 35 on said shafts 9 and 10, are gears 11 and 12, with which mesh two intermediate gears 13 and 14, which also mesh with each other. The axes of the gears 13 and 14 are connected, respectively, with the shafts 9 and 10 by 40 means of links 15 and 16, while the axes, or shafts, of the gears 13 and 14 are connected to each other by means of a link 17.

The link, or lever, 15, is extended beyond the link 17, as at 15^a, and has attached to its 45 upper end an operating link 18.

By means of this operating link 18, the lever, or member 15, can be rocked to the position shown in dotted lines, which move the gears 13 and 14 into the positions indicated 50 by the dot-dash circles. This movement also operates to rotate the gears 13, 14 and 12 and to move the eccentric member 6 into the position shown in dotted lines. The gear 11, however, and the eccentric member 5, are not 55 moved. Also mounted on the shaft 9, is a pulley 19, adapted to be driven from any

source of power by means of a belt 20. Thus by this means the gear 11, may be driven, which will also drive gears 13, 14 and 12 in unison, or at the same speed, inasmuch as they are shown to be of the same size. Different results can be had, of course, by changing the sizes of the gears. It will be apparent that with the parts in the positions shown in full lines, that the eccentric 60 levers 5 and 6 will move together, and that the cross beam, or lever 4, will operate the piston or plunger 2, without any effective rocking movement of said cross beam, or lever. When the operating lever 18, however, is moved to the extreme right position, indicated in dotted lines, the gears 13, 14 and 12, are turned as the gear 13 travels around the gear 11, and the eccentric member 6 is moved to its uppermost position, as shown in 65 dotted lines. In this position, as said gears are driven through the pulley 19, the eccentric levers 5 and 6 are operated alternately up and down, thus transmitting a rocking movement to the cross beam, or lever, 4, 70 which results in a minimum movement to the piston 2. By moving the controlling lever 18, to any intermediate position, between the position shown in full lines and in dotted lines, any desired intermediate stroke or 75 movement of the piston or plunger 2 can be secured, thus making it possible to get a very nice adjustment, or control movement, for a piston, plunger or other oscillating element. 80

It will also be noted that this adjustment can be made very easily and without stopping or interfering with the operation of the device. 90

While I have shown and described my 95 variable stroke mechanism as connected with a plunger, or piston, operating in a cylinder, it is to be understood that it can be interposed in connection with the drive of any driven element, whereby to vary the 100 stroke, or movement, thereof, and I do not, therefore, limit my invention to the particular embodiment thereof here shown for purposes of illustration except as I may be limited by the hereto appended claims. 105

I claim:

1. A variable stroke mechanism comprising in combination with an element to be moved, a pair of eccentrics with eccentric straps connected with said element, means 110 for driving said eccentrics together, and means common to both for changing the

relative positions of said eccentrics, whereby to vary the reciprocating movements of said eccentric straps relative to each other.

2. A variable stroke mechanism comprising in combination with an element to be moved, a cross beam or lever connected to said element, a pair of eccentrics with eccentric straps connected to the opposite ends of said cross beam, means for driving said eccentrics together, and means common to both for changing the relative positions of said eccentrics, whereby to vary the reciprocating movements of said eccentric straps relative to each other.

10 3. A variable stroke mechanism comprising in combination a reciprocating element, two eccentrics with eccentric straps connected therewith, driving gears for said eccentrics, intermediate gears connecting the 20 gears of said eccentrics, and means for moving said intermediate gears relative to said eccentric driving gears, whereby one of said eccentric driving gears is rotated to change the position of its eccentric relative to the 25 other eccentric.

4. A variable stroke mechanism comprising in combination with an element to be moved or oscillated, a cross beam, or lever, connected intermediate its ends with said

element, a pair of eccentrics with eccentric 30 straps connected to the opposite ends of said cross beam, or lever, gears for driving said eccentrics, intermediate gears intermeshing with said eccentric driving gears, and means for moving said intermediate 35 gears relative to said eccentric driving gears, whereby to turn said eccentrics relatively to each other, substantially as described.

5. A variable stroke mechanism comprising in combination with an element to be reciprocated, a cross beam, or lever, connected therewith, a pair of eccentrics with eccentric straps connected with the opposite ends of said cross beam, or lever, means for driving one of said eccentrics, connecting means 40 therefrom to the other of said eccentrics, whereby said eccentrics are driven together, and means common to both for changing the positions of said eccentrics relative to each other without interrupting the driving connections therebetween, substantially as and 45 for the purpose described.

Signed at Portland, Multnomah county, Oregon, this 21st day of December, 1916.

EMIL CHRISTENSEN.
